United States Patent Office.

THOMAS J. SMITH, OF JACKSON, MICHIGAN.

Letters Patent No. 84,141, dated November 17, 1868.

APPARATUS FOR RAISING FENCES.

The Schedule referred to in these Letters Patent and making part of the same.

To whom it may concern:

Be it known that I, THOMAS J. SMITH, of Jackson, in the county of Jackson, and State of Michigan, have invented a new and useful Improvement in Adjustable Apparatus for Raising Wagons and Fences; and I do declare that the following is a true and accurate description thereof, reference being had to the accompanying drawings, and to the letters of reference marked thereon, and being a part of this specification.

The nature of my invention consists in the attachment to a carriage or wagon-jack of a hook, in such a manner that fences, &c., may thereby be lifted from the ground.

A represents the standard, provided with a slot, B, said slot having hooked projections c, in which the pivot D of the lever E rests, which latter is stayed to standard A, by means of rod F catching in notches G on standard

A. To the short arm of lever E is pivoted a hook, H, which is intended to engage with the bottom rail of a fence, and, by means of the lever E, to elevate it when desired.

By this attachment to a wagon-jack—an instrument used on every farm—a cheap and effective fence-lifter is produced.

Having thus described my invention,

What I claim as new, and desire to secure by Letters Patent, is—

The combination, with the lever of a carriage-jack, of a hook, H, substantially as and for the purpose described.

THOS. J. SMITH.
